UNITED STATES PATENT OFFICE.

WILLIAM A. CHILDS, OF ENGLEWOOD, NEW JERSEY.

TELEPHONIC EXCHANGE SYSTEM AND DEVICE.

SPECIFICATION forming part of Letters Patent No. 225,797, dated March 23, 1880.

Application filed January 24, 1880.

To all whom it may concern:

Be it known that I, WILLIAM A. CHILDS, of Englewood, in the State of New Jersey, have invented a new and useful Improvement in 5 Telephonic Exchange Systems and Devices, of which the following is a specification.

My invention relates to an improved system and improved apparatus in telephone-exchanges, which have for their object the prevention of the confusion, mistakes, and delays which have hitherto been found to occur at central offices or exchanges where subscribers' wires are connected at their request, particularly where but one wire is used between the 15 subscriber's station and the central station.

My invention also relates to similar appliances and methods of operation extended to or used between two or more central offices for the purpose of effecting connections and 20 intercommunications between the subscribers whose wires terminate in any one of such central offices.

In the drawings, Figure 1 is a plan of a switch-board, of table-operator rooms, of the 25 arrangement of circuits, and of the location of the listening and switch-board operators. Fig. 2 is a view of the wedge W'; and Fig. 3 is a plan showing two or more central offices connected by trunk-lines and inter-office listening-lines; and Fig. 1' is a section on line x x, Fig. 30 1, showing the wedge W in place.

The series of bars represented in the drawings as connected to lines marked from 101 to 132, and crossed at right angles by similar bars marked from 1 to 16, constitute a switch-board placed at the central station or office, and used as the means for connecting any two subscribers' wires and subscribers of the telephone-exchange. These connections 35 are made by inserting properly-shaped metal wedges, to be hereinafter described, between any two bars where they cross each other, space being left for inserting the wedge.

Instead of the switch-board thus described 45 I contemplate the use of any other suitable switch-board, and I have used switch-boards having horizontal bars only, and, instead of the vertical bars, pieces terminating in flexible cords provided with plugs to fit holes pierced 50 in the horizontal bars to receive them; and any two lines are connected by inserting their

plugs in any one of the horizontal bars. At or just below the bottoms of each vertical bar are formed a series of annunciators having thereon numbers from 101 to 132, corresponding to the numbers of the wires from which they are pendent, or rather to which they are connected, by means of the wedges W W W. Below these annunciators runs a wire, G, to which are attached connections, which complete any of the circuits from 101 to 132 through a ground-connection. These bars may be increased as the number of subscribers increases.

The cross-bars, one (1) to sixteen, (16,) or more, as the case may be, are divided into 65 clusters—say of four, (4,) or any other convenient number, each cluster being lettered A B C D, &c., or otherwise indicated, and connected with the tables of the table-operators in sections A B C D, &c., as indicated at the 70 right of the switch-board, and in the usual manner.

L is a line of wire common to all the sections A, B, C, and D, &c., which is provided with a battery, B, extends to the indicator-frame A B C D, &c., at the left of the switch-board, and has return-wire L' extending from each particular indicator-letter to the section with which the same cluster is connected, as from A to A, B to B. These circuits are used to 80 open or close the indicators, to show whether the operators in sections A B, &c., are occupied or not. The switch-board is divided vertically into sections of eight (8) wires each, as shown, each section to be placed in charge of 85 a switch-board operator at S S' S² S³. The sections should contain as many bars and circuits as each switch-board operator can attend to.

B' B' are batteries, one for each room or 90 section A B, &c., all connected with the line L², which has the ground-connection G'. These batteries are used by the table-section operators to "ring up" any subscriber wanted.

So far as these parts of the apparatus and 95 the system hereinbefore described are concerned they work reasonably well when the calls for connections are not very numerous or not simultaneous; but as these approach somewhat to the capacity of the appliances, and especially when many calls come together, a babel of confusion begins to reign, owing to the 100

shouting back and forth between the table-operators and the switch-board operators, resulting in frequent mistakes and delays and in imperfect service generally.

5 These objections my invention is intended to remedy by adding the following appliances and arrangements: First, connect the table-sections A, B, C, D, &c., by means of a common circuit, O', which I call the "office-circuit," with 10 a pair of telephones located near the switch-board and near the positions of the switch-board operators S, S', S², and S³ in front of the same. Second, provide in each table-room or section switches O² O³, arranged so as to 15 enable the table-operators to transfer their pairs of telephones from the switch-board circuits, and connect them with the office-circuit O' at will. Thus the table-operators can communicate either with any subscriber or with the 20 listening-operator O through the same pair of telephones, switching them from one line to the other, and thereby diminishing the liability to confusion and misunderstanding which might arise if the instruments were permanently 25 connected into the circuits, and thereby placed, to some extent, out of the control of the operator in the room. Third, I isolate the table-operators from each other and from the main or switch-board room and operators 30 there, placing them apart, preferably in separate rooms, so that they may not overhear or confuse each other and the switch-board operators in giving orders for connections and disconnections. Fourth, I place a listening operator, 35 O, at the end of the office-circuit O' in front of the switch-board, which is connected with a pair of telephones for his use; and, fifth, I provide a switch-board so arranged that a metal wedge inserted between the vertical and 40 horizontal switch-bars with great facility makes the switch-board connections.

My method of operation is then as follows: Supposing that the subscriber on circuit No. 132 desires to communicate with the subscriber 45 on circuit No. 101: when he drops the annunciator No. 132 in the usual manner the switch-board operator at S³, noticing it, glances at the indicator on the left of the switch-board to see which letters are uncovered, indicating that 50 the table-operators occupying rooms or tables indicated on the right of the switch-board by similar letters are disengaged, and selecting on such, say D, he also selects a bar of the cluster marked D not in use—say 15—and 55 throwing a battery provided for the purpose into the circuit by touching a battery-pin, P', thereto, thereby drops the annunciator 15 in room or section D, and immediately connects 132 and 15 by inserting the wedge W of 132 60 in between the bars at the crossing of the two switch-bars of that number, whereupon D, observing annunciator 15 in his room to drop, switches his pair of telephones into connection with the switch-bar 15 by means of his wire 65 of that number, thereby establishing communication with the subscriber 132, of whom he asks the name or number of the subscriber

with whom he (132) desires to communicate. For brevity's sake, this is usually done by saying "hello;" and 132 replies "132 101," or gives 70 the name of the party desired, whereupon D, selecting some disengaged bar leading to his room—say 16—switches his telephones out of circuit 132 into the office-circuit O', and instructs the listening operator O, who sits listening for such orders from A, B, C, and D, to direct the switch-board operator at S to connect 101 and 16, upon receiving which order S touches the battery B² to the bar 16, drops the annunciator of that number in 80 room D for the information of the operator there, and immediately connects 101 and 16, as requested. Then D immediately proceeds to call subscriber 101 by touching the wire of the battery B' to the wire 16, and when 101 85 responds he (D) connects the wires 15 and 16, thereby establishing telephonic communication between 132 and 101.

In order to know when the communication is completed, so as to disconnect at the proper 90 time without listening to the conversation of the subscribers, D may keep one or both of the annunciators 15 or 16 in circuit, or he may have a special one arranged in any usual way, which can be dropped by either 132 or by 101, 95 and notice be thereby given to D, who, in turn, notifies the listening operator O to disconnect, switching his telephones into the office-circuit O' for that purpose, whereupon O, in turn, instructs the switch-board operators S and S³ to disconnect 132 and 101 in the main-office switch-board. S³ thereupon disconnects 132, and restores the annunciator 132 to its place in connection with the bar 132, so as to be ready for any further notices, and S does the same thing for 101.

When the switch-board operator S³ first connects 132 and 15, as hereinbefore described, he immediately closes or covers the letter D in the indicator-frame at the left of the switch-board, which is arranged for that purpose, either by an independent circuit, H and H', connected therewith, or by mechanism operated by hand. The object of so covering or closing the letter D is to indicate that the table-operator D is for the time being engaged. The switch-board operator S³, instead of glancing at the indicator on the left in the first instance, when annunciator No. 132 drops, may use the bars themselves as indicators to guide 120 him, using any one which he finds free for his purpose.

At the time when the table-operator D completes the telephonic communication between subscribers 132 and 101, where the way is 125 clear for that purpose, and also when he finds that 101 is busy, he (D) touches a "push-button" provided for that purpose, thereby connecting together the wire L and that one of the wires L' leading to his room, and uncovers 130 the letter D in the indicator at the left of the switch-board, the object of which is to inform the switch-board operators that the table-operator D is disengaged. Both or either of these

operations may be executed mechanically; but I prefer to use a battery and circuit associated with the usual mechanical applicances for operating disks or other closing devices.

5 So far I have described the steps taken when the way is clear for the desired connection and communication; but when 132 desires to communicate with 101, and 101 is engaged in communication with some other subscriber, the 10 method of operation is as follows: Passing through the operations before recited, when the operator at S receives his order from O and attempts to fill it he discovers that the wedge W, 101, is out of its regular place above the annunciator, which indicates to S that 101 is otherwise engaged, whereupon he (S) takes a wedge made of non-conducting material, to avoid making any connection between the bars having the letter D thereon, and inserts 15 it between the annunciator 101 and its bar to indicate that the table-operator D is waiting for 101, and at the same time he says to O, in whose presence he is, that "101 is busy," and O repeats the remark to table-operator D, 20 through the office-circuit O' and its telephones, D having retained his telephones in circuit for that purpose, waiting the dropping of the annunciator 16, as before stated, or notice that 101 is busy, as the case may be. Thereupon 25 D informs 132, by telephone switched into that circuit, 101 is busy, and makes a suitable memorandum of the fact for his own future guidance, or possibly depends upon his memory in that regard, also sending an order to the listening operator O to order 132 and 15 disconnected. 30 When 101 is disengaged an order to disconnect him is received by the switch-board operator S through the listening operator O and the table-operator in the particular room 35 through which 101 was engaged; then S disconnects him, but in attempting to restore his wedge W to its proper place discovers the non-conducting wedge with the letter D, indicating that D is waiting for 101, and thereupon connects 101 with any disengaged bar 40 and wire leading to room D, at the same time ringing up 101 by a battery provided for that purpose, or leaving D to do so by his battery B'. Either of these methods found most convenient 45 may be adopted. D, on discovering with whom he is connected, by switching in his telephone recalls the fact that 132 is waiting for 101. He then rings up 132 and connects 132 and 101 together, as before described, 50 with the proper annunciator or annunciators in circuit, to be dropped when the subscribers have completed their communications.

Of course any other two subscribers' stations 55 may be connected and disconnected in a similar manner. I prefer to have the office-circuit a metallic circuit complete in the central office and associated table-operator rooms, but of course a ground-circuit may be used; and when the distance is short a speaking-tube 60 may be substituted for this circuit as a means of communication between the table-operators and the listening operator.

When the business of the office requires it more than one office-circuit, O', may be provided with a listening operator for each circuit; and such additional circuits may extend between the same rooms or tables A B C D, or to still others having a part of the same business and corresponding functions and methods of operation. There may also be two 75 or more table-operators in each room A B, &c., and one may have charge of connections while the other has charge of orders for disconnection.

I also extend trunk-lines 10 to 15, Fig. 3, 80 between two or more central offices, through which connections may be made between the subscribers centering at any two central offices; and to operate these trunk-lines I extend another line or lines, O⁴, between these central offices, over which the orders for that purpose are sent, and place a listening operator, O³, at each central office on this line.

Now, when a subscriber, say No. 104, (in Fig. 3,) connected with central office No. 1, 90 wishes to communicate with subscriber, say, No. 304, who is connected with central office No. 3, the order of proceeding is as follows: He drops his annunciator No. 104 in central office No. 1 and is connected by one of the 95 short wires, say No. 4, with room-operator B, as before described. B then receives the order from 104, selects a disengaged short wire leading to the switch-board, say No. 3, and instructs the listening operator O on the office-wire O' to connect 304 with 3, who, in turn, repeats this order to the switch-board operator S. S then selects a disengaged trunk-line, say No. 13, leading to central office No. 3, and connects it in the manner already described 100 with wire No. 3, and at the same time instructs the listening operator O³ on the line O⁴, extending between the central offices, to instruct central office No. 3 to connect subscriber 304 with trunk-line No. 13. Central office No. 3 executes this order in the manner as before described, whereupon room-operator B in central office No. 1 thereby obtains direct connection with the subscriber wanted—No. 304—and immediately proceeds, 110 as described in the first instance, to "ring him up" and connect him with the subscriber No. 104, who called for him, precisely as if he were a subscriber connected originally and directly with central office No. 1. The disconnection 115 is accomplished by a similar series of orders to that heretofore described in the first instance, where disconnection is ordered.

In case No. 304 is busy the switch-board operator S of central office No. 3 inserts a non-conducting wedge bearing the number 1 between the bar 304 and its annunciator to indicate that central office No. 1 is waiting for No. 304. He (S) sends word to office No. 1 that 304 is busy, which is communicated to 120 104, and the proper memorandums are made at both offices, so that when 304 is disengaged notices may be given and the proper connections then made.

In the absence of trunk-lines 12 and 13, or at will, the lines 10 or 11 and 14 or 15 may be used in their stead, the orders and the connections being repeated and completed through central office No. 2, and its operators and apparatus operating in a similar manner.

When telephone-exchanges are operated in the manner herein described, whether between subscribers and their central office or between the subscribers of any two central offices through trunk-lines, the business is compelled to come in systematically and in order, since the table-operator can at once ascertain whether any other table-operator is giving orders, and thus be enabled to take his turn without creating confusion either between himself and other table-operators, between himself and the switch-board operators, or between the switch-board operators themselves.

The wedges W' W' are made as shown in Fig. 2, and are used instead of the plugs heretofore used to insert in holes made in the two switch-board bars at the crossing-points. These wedges are preferably made with handles, hard rubber or other suitable black material being preferred, the metal part M, consisting of a strip of thin spring-steel, extending longitudinally through a part of the handle, one end being bent first down and then up, so as to form the wedge W', and the other end being turned up, so as to face the end of the handle entirely with metal to make contact as certain as possible.

The vertical metal bars V are insulated from each other by means of rubber or other non-conducting strips R, which project beyond the faces of the bars and are crossed by horizontal bars V', which rest on the rubber strips, or are otherwise insulated from the vertical bars, and are separated from each other and from the vertical bars a sufficient distance to allow of the easy insertion of the wedges between them both, and also the easy removal of the same. Instead of using strips of spring-steel, I contemplate using a solid metal wedge of any kind and form capable of being inserted between the bars at their several points of crossing; but I prefer the spring-wedge shown and described, as it yields while being inserted and works better in some respects than a solid wedge of the same size would do. In my invention no holes are made at this point; but in inserting the insulators between the bars space is left, so that the wedges W' W' being inserted between them electrical contact is made, and being removed is broken. Contact is effected in this way with greater certainty and facility, and the cost of the switch-board is materially reduced.

Such a switch-board is not confusing to the eye, as the old one is, and enables the operator to ascertain more promptly and certainly whether the bars are engaged or disengaged. The great number of holes in the old form of

switch-board presents an appearance which is injurious to the eyes of the operators as well as confusing, while the plane surface of my switch-board is not so.

In using the term "table-operators" I do not intend to limit such operators to the use of tables, as their instruments and devices may be connected to any other convenient furniture for the purposes and uses described. The term is not, therefore, descriptive, but is used for convenient designation.

I hereby disclaim, so far as this specification and these Letters Patent are concerned, all the inventions shown, described, and claimed, or to be claimed, in my earlier application, filed November 29, 1879, and not claimed herein; and this disclaimer is in favor of my said last-mentioned application only. This disclaimer is intended to cover, and does cover, every invention not specifically claimed in the four claims of this specification, and all inventions shown, described, or otherwise found herein, and also in the original application, but not so claimed herein, are left in the original application filed November 29, 1879.

I claim as my invention—

1. In a telephone-exchange system, an office-circuit, O', for the use of a listening operator, O, interposed between the table-operators and the switch-board operators, for the purpose of conveying orders *seriatim* between them for the making and the breaking of connections.

2. In a telephone-exchange system consisting of two or more connected central offices, an inter-office circuit, O⁴, for the use of listening operators O³, interposed between two or more central offices and the table and switch-board operators of each, for the purpose of conveying orders *seriatim* between them for the making and the breaking of connections between the subscribers' wires of each central office, in the manner shown and described.

3. As an improvement in the method of operating a telephone-exchange central office, locating a listening operator, O, between the table-operators and the switch-board operators to transmit the orders and notices between them, in the manner and for the purposes set forth.

4. The office-circuits O', the inter-office circuits O⁴, the trunk-lines between central offices 1, 2, and 3, suitable switch-boards at each office, indicator-circuits L L' and H H', table-operator circuits L², and subscriber-circuits 101 102, &c., combined in one system, in the manner and for the purposes set forth.

In testimony whereof I have hereunto set my hand this 23d day of January, 1880.

WM. A. CHILDS.
